UNITED STATES PATENT OFFICE.

FRANK J. SPRAGUE, OF NEW YORK, N. Y., ASSIGNOR TO THE SPRAGUE ELECTRIC RAILWAY AND MOTOR COMPANY, OF SAME PLACE.

ELECTRIC-RAILWAY MOTOR.

SPECIFICATION forming part of Letters Patent No. 431,823, dated July 8, 1890.

Application filed June 11, 1889. Serial No. 313,874. (No model.)

To all whom it may concern:

Be it known that I, FRANK J. SPRAGUE, a citizen of the United States, residing at New York city, in the county and State of New York, have invented a certain new and useful Improvement in Electric-Railway Motors, of which the following is a specification.

My invention relates to certain improvements in the manner of arranging and supporting electric motors upon wheeled cars or vehicles for propelling the same, and in the construction of such cars or vehicles designed for propulsion by electric motors.

The object of my invention is generally to provide a secure and convenient attachment and arrangement for one or more motors upon the electrically-propelled car or vehicle in which space will be economized, the motor or motors and the car-body will be so independently supported as not to be affected by each other's weight and movements, the weight of the motor or motors will be evenly distributed, the motor or motors will be so supported that they will have the minimum of bodily movement, and the gearing which transmits motion from the motor-shafts to the driving-axles shall have a constant effective engagement.

I prefer to make use of my invention in connection with vehicles having vertically-movable axle-boxes, and in carrying my invention into effect with such vehicles I employ equalizing-bars, which extend on each side of the vehicle from one axle-box to the other, and I join such equalizing-bars by a cross piece or frame which forms the immediate support for one end of the electric motor, the other end being centered on a driving-axle of the vehicle with which the armature-shaft of the motor is suitably geared or mechanically connected by a suitable centering support which is independent of the frame formed by the equalizing-bars, whereby the gearing between the armature-shaft and the axle is made to maintain constantly an effective engagement. The suspension of the motor from the cross piece or frame is preferably a flexible suspension through springs or other flexible supports. When two motors are provided, I support them both in this way, one being placed before and one behind the said cross piece or frame, and I center each

motor upon one of the driving-axles with which its armature-shaft is geared or mechanically connected. The body of the car I support upon springs independent of the cross piece or frame which supports the motor or motors, so that the movements of the car-body upon said springs are not communicated to the motors.

My invention is illustrated in the accompanying drawings, in which—

Figure 1 is a top plan view of a truck embodying my invention; Fig. 2, a longitudinal vertical section of the same on the line 2 2 of Fig. 1; Fig. 3, a side elevation of the truck with the motor omitted and one of the axle-boxes in vertical section.

The truck shown is of that character in which the car-body has a pivotal movement upon the center of the truck.

A are driving-axles of the truck and B B the wheels thereof, the axles turning in axle-boxes C outside the wheels, and the axle-boxes being vertically movable in the pedestals C'. From one axle-box to the other on each side extend the equalizing-bars D, such bars being so attached to or supported upon the axle-boxes at their ends as to have a limited play or movement.

O is a frame carried above the equalizing-bars D and connected therewith through the spiral cushioning-springs F F.

E is the spring-board or sand-board which supports the car-springs, and which is hung from longitudinal girders of the frame O by stirrups O'. The elliptic car-springs Q are mounted upon the said board, and these support the cross-bolster P, which has at its center the pivoting-support for the car-body, the car-body being thus carried upon the springs Q. In order that the propelling electric motors may be made independent of the said springs which support the car-body and also to secure the other advantages heretofore pointed out as the object of my invention, I support and arrange said motors in the following way:

The motors shown are circular in form, S S being the field-magnet windings and G the armature of each motor. Each motor is centered on the driving-axle at one end of the truck, for the purpose already described, by

means of sleeves *e e*, and brackets *N*, extending from one pole-piece to the other, support the armature-shaft of each motor. Upon each end of each armature-shaft is a pinion 5 *H*, and these pinions engage toothed wheels *M* on the driving-axles to turn the same.

From one side of frame *O* to the other there extend two pairs of cross-bars *a* before and behind the cross-springs *Q*, but independent 10 of the said springs. These cross-bars support the motors, the motors being flexibly connected therewith. Such flexible support for each motor is by means of a bolt *b* passing through a lug *c* projecting from the motor, which bolt passes also through a box *h*, supported from the pair of cross-bars *a*, and within said box *h* is a spring *d*, so that through the bolts *b*, springs *d*, cross-bars *a*, frame *O*, and springs *F* the motors are flexibly supported from the equalizing-bars, which are connected with the axle-boxes.

What I claim is—

1. A wheeled truck provided with springs for supporting a car-body and carrying an electric motor flexibly supported upon it, said motor being centered upon an axle of the truck with which its armature-shaft is mechanically connected, substantially as set forth.
2. The combination of a wheeled truck, springs on said truck for supporting a car-body, and an electric motor carried by said truck independent of said springs and centered upon an axle of the truck with which 30 its armature-shaft is mechanically connected, substantially as set forth.
3. The combination of a wheeled truck, springs on said truck for supporting a car-

body, and an electric motor flexibly supported by said truck independent of said springs and 40 centered upon an axle of the truck with which its armature-shaft is mechanically connected, substantially as set forth.

4. The combination of a wheeled truck, springs on said truck for supporting a car-body, a frame joining the axles of said truck, and an electric motor carried by said frame independent of said springs and having a centering-support independent of the said frame upon an axle of the truck with which 45 its armature-shaft is mechanically connected, substantially as set forth.

5. The combination of a wheeled truck, springs on said truck for supporting a car-body, a frame joining the axles of said truck, and an electric motor flexibly supported by 50 said frame independent of said springs, and having a centering-support independent of said frame upon an axle of the truck with which 55 its armature-shaft is mechanically connected, substantially as set forth.

6. The combination of a wheeled truck, a frame yieldingly supported upon the axles of said truck, springs on said truck for supporting a car-body, and an electric motor carried 60 by said frame independent of said springs and having its armature-shaft mechanically connected with one of said axles, substantially as set forth.

This specification signed and witnessed 70 this 10th day of June, 1889.

FRANK J. SPRAGUE.
